(57) **CLAIM**

The ornamental design for a medical measurement apparatus for optics, as shown and described.

DESCRIPTION

1. Medical Measurement Apparatus for Optics

FIG. 1.1 is a front view of a medical measurement apparatus for optics showing our design in a first position of use; FIG. 1.2 is a front view thereof in a second position of use; FIG. 1.3 is a front view thereof in a third position of use; FIG. 1.4 is a perspective view thereof in a first position of use; FIG. 1.5 is a perspective view thereof in a second position of use; FIG. 1.6 is a perspective view thereof in a third position of use; FIG. 1.7 is a rear view thereof in a first position of use; FIG. 1.8 is a perspective view thereof in a second position of use; FIG. 1.9 is a perspective view thereof in a third position of use; FIG. 1.10 is a rear perspective view thereof in a first position of use; FIG. 1.11 is a rear perspective view thereof in a second position of use; FIG. 1.12 is a rear perspective view thereof in a third position of use; FIG. 1.13 is a bottom view thereof in a first position of use; FIG. 1.14 is a bottom view thereof in a second position of use; and FIG. 1.15 is a bottom view thereof in a third position of use.
